INDEX OR INFORMATION RACK.

1,106,344.

Specification of Letters Patent. Patented Aug. 4, 1914.

Application filed February 24, 1913. Serial No. 750,269.

To all whom it may concern:

Be it known that we, WILLIAM P. DE SAUSSURE, Jr., and GEORGE S. TIFFANY, citizens of the United States, residing, respectively, at Englewood Cliffs, Bergen county, New Jersey, and Summit, Union county, New Jersey, have invented certain new and useful Improvements in Index or Information Racks, fully described and represented 10 in the following specification and the accompanying drawings, forming a part of the same.

Our invention relates to index or information racks, and more particularly to a type 15 of sectional rack of variable capacity adapted to have the index elements changed as desired, so as to especially adapt the rack for use as a directory for hotels, buildings or other analogous purposes.

20 The main object of the invention is to provide an index or information rack wherein separate sheets or cards are carried by independently removable holders which may be inserted at or removed from any point of 25 the rack so that the entire capacity of the rack may be utilized and the removal of any index sheet or card will leave no blank spaces in the rack.

A further object is to provide a rack of 30 this character wherein index sheets or cards of light weight may be used so as to permit the simultaneous production of a plurality of such sheets or cards by means of carbons, or other duplicating means, thus simplifying the labor of preparing index cards 35 for a plurality of racks such as are ordinarily used in a hotel.

A still further object is to provide an index or information rack wherein the card 40 holders will be nested in a manner to expose only a portion of each index sheet or card, thus not only providing a condensed index structure, but permitting the placing on the sheet or card of private data which 45 will be concealed from view while the index support is in the rack.

A still further object is to provide an index or information rack wherein each sheet 50 or card holder will be held in position in the rack and yet be capable of being quickly placed therein or removed therefrom without removing any other holder from the rack.

A still further object is to provide an index or information rack of this character

wherein the various sheet or card holders will be so interlocked as to prevent the removal of any one of them without first disengaging it from the adjoining holder.

A still further object is to provide a rack 60 of this character wherein the nested index sheet or card holders may be divided into independently operative groups so as to permit the handling of one group without disturbing or handling other groups, thus 65 facilitating the insertion or removal of different holders.

A still further object is to provide a rack 70 of this character wherein the partitions or supports defining the size of the different groups may be adjusted in the frame to vary the size of such groups.

A still further object is to provide a rack 75 of this character wherein, in addition to the index sheets or cards, signal cards may be used and exposed in a manner to indicate that special attention to any particular index sheet or card is required.

A still further object is to provide a rack 80 of this character wherein all of the sheet or card holders when in the nested position will be firmly held against displacement through a support or partition locked to the frame of the rack and the interlocking means carried by the various independent holders. 85 And a still further object is to provide a rack of this character which may be speedily made up or changed, and wherein the various indices or information sheets or cards may be inserted in a manner to permit an alphabetical or chronological listing without disturbing the order of the entire rack. 90

The invention consists primarily in an index or information rack embodying therein a frame, a plurality of independently removable holders mounted therein, and means carried by each said holder whereby an index sheet or card may be detachably mounted therein; and in such other novel features of construction and combination of parts as are hereinafter set forth and described, and more particularly pointed out in the claims 95 hereto appended.

Referring to the drawings:—Figure 1 is a front elevation of an index or information rack embodying our invention, three sections being shown therein, but only one being shown as containing the card holders; Fig. 2 is a side elevation thereof; Fig. 3 is a front view of a single section upon a 100 105 110

larger scale; Fig. 4 is a vertical section of the rack section shown in Fig. 3, with the index sheet or card holders removed therefrom; Fig. 5 is a detail view in section showing three card holders in position supported by the base support; Fig. 6 is a front view of one of the holders, showing the manner of mounting the index card or sheet therein; Fig. 7 is a side view of one of the holders; Fig. 8 is a vertical section of the holder with an index card or sheet therein; Fig. 9 is a horizontal section taken on line 9—9 of Fig. 4; Fig. 10 is a horizontal section of the frame taken on line 10—10 of Fig. 4 showing one of the adjustable supports; Fig. 11 shows one of the special signal cards; and Fig. 12 is a view showing a modified form of frame and index sheet or card support.

Like letters refer to like parts throughout the several views.

In the embodiment of our invention shown in the drawings, we provide a structure embodying a plurality of units or frames so mounted as to permit the increase or decrease of the number of these units at will, thus imparting to the structure expansibility or elasticity, as to the capacity thereof, beyond that expansibility and elasticity inherent to each unit by reason of the removability of the individual card holders. These units or frames are indicated in Fig. 1 as 1, 2, and 3, and each preferably comprises side rails a and a' connected by tie rods a^2 , the top a^3 and the base or sill a^4 , which construction not only permits the desired rigidity of frame, but at the same time results in a structure of light weight.

Upon opposite sides of each unit or frame are vertically extending side flanges b and c , one of which as b , in the preferred form of the invention, is provided with an overhung flange b' adapted to hold independently movable holders in position upon the frame. By this construction, we provide means whereby the accidental displacement of any holder is prevented, and also afford a bearing surface against which the holders may rest and upon which they may have movement in inserting a holder in, or removing it from, the frame. The top a^3 projects across the channel formed by the flanges b and c and thus prevents sufficient vertical movement of the individual holders to permit the escape thereof from the frame.

The bottom end of the frame is adapted to be seated in a channeled keeper d which is secured in any desired relation, as to a wall, by the brackets d' , the frame being tilted backwardly so as to rest against the wall or other support and thus cause all of the holders to bear upon the rails b c , or other seat therefor, upon the frame. The

channeled keeper d may be of any desired length to admit of the expansion of the rack to any desired extent by the addition of units or frames as required.

In conjunction with each unit or frame, we provide a plurality of independently removable holders h for index sheets or cards, adapted to seat between the flanges b and c and be positioned in the frame thereby. These holders are of uniform size and formation and are adapted to fit any portion of the frame and to be so nested together as to insure compactness in the index, while affording ample space for the inclusion upon the sheet or card of explanatory matter of any kind which will not be exposed to view.

To enable index sheets or cards to be held extended in said holders, we form each of them with a back plate e having a front supporting and retaining flange f extending upward from the lower edge thereof, said flange being best of such length and height or width as to hold the sheet or card close against the face of the plate e . By this construction, index sheets or cards of flexible, light-weight paper may be used, thus permitting the use of carbon sheets or other duplicating means to produce the matter upon several index sheets or cards simultaneously. Oppositely disposed to the retaining flange f is a flange g projecting forwardly from the plate e ; which flange has the threefold function of protecting the top of the index sheet or card, aiding in holding it in place, and serving as a finger grip in raising one or more supports when inserting supports in, or removing them from, the frame or unit. The ends of back plate e are adapted to pass one under the flange b' and the other within the flange c , both ends when the holder is in position seating on the bearings within the flanges b and c . Projecting from the back of the plate e is an upwardly opening keeper or socket j , which keeper is adapted to receive and retain the lower part of the holder next above it and interlock therewith in a manner to prevent, in conjunction with the flanges b and c , the removal of any holder unless the holder next above has been raised to disengage it therefrom. By forming and nesting the holders in this way any backward pressure on a holder in lifting or raising it will be away from the holder below so that there will be no tendency of adjoining holders to bind as one or more of the holders are raised to permit the removal or insertion of another or others at any point of the frame.

To hold the bottom holder in position and to prevent the lifting of one side of all of the holders in a column group of holders simultaneously, we provide at the bottom of the frame a base support formed with locking

means which may consist of a pocket formed by oppositely disposed tongues or plates k , k' carried by the base a' , which pocket is adapted to receive the lowermost holder of the group and hold it in position. The forward tongue or plate k may be of a height to conceal the major portion of the lowermost support so as to leave only the top of it exposed for index purposes. The tongue or plate k is inclined forwardly relatively to the frame and the rear tongue or plate k' is of a height to engage the socket or keeper j of the lowermost holder so as to hold it tilted forward at an angle to the frame so that the next holder when slid down into place will enter behind the lowermost holder and take its position properly with its lower edge within the socket or keeper of the lowermost holder. The construction of this support is shown most clearly in Figs. 5 and 9.

When it is desired to separate the column of holders in the frame into one or more independently operative groups, we provide detachable, adjustable partitions or supports having oppositely disposed tongues or plates l and l' , such supports being adapted to be secured in desired position to the rails a and a' by bolts m and a clamping plate m' . The plates l and l' form a pocket similar to that formed by the tongues or plates k and k' , and have the same function and mode of operation. The construction of these adjustable supports or partitions and the manner of adjusting them upon the rack is best shown in Figs. 4 and 10.

While in actual practice we prefer to use the form of support and frame heretofore described, if desired this may be modified, as shown in Fig. 12, by providing each side rail of the form with overhung retaining flanges as shown at b' and c' . When using a frame of this construction, the holders may be inserted and removed by being so constructed as to permit a rotative movement thereof within the flanges b' and c' , as by forming them with their ends curved on an arc about a central point.

We prefer the form of the invention shown in Figs. 1 to 10, however, because it permits the removal or insertion of a single holder with an upward movement thereof sufficient merely to clear the socket or keeper of the next lower holder, thus avoiding excessive space at the top of each frame or unit to allow for the movement of the upper holders necessary to permit the disengagement of the holder to be removed or the insertion of another holder.

Under some conditions of use, it is desirable to provide special service signals to call to the attention of the user that certain index sheets or cards require special attention. To meet this requirement, we provide signal cards which should differ in color or character from the main index sheet

or card, and which are adapted to be inserted in a holder in front of the regular index card or sheet and of shape and size to be visible when the holder is nested with others in the frame, while covering only a part, and preferably only a small part, of the sheet or card to which it is applied. Such signal cards may be of the form shown in Fig. 11 or of other suitable shape. A signal card of the form shown will appear as shown at s in Fig. 3 when in use. By the use of such a signal sheet or card, the attention of a clerk is directed to the matter to which the signal relates before any service is given to or affecting the person indicated by the index card or sheet to which the signal card is applied.

In the use of our improved index or information rack, the channel d is installed in any desired relation and one or more units or frames mounted therein in the manner shown in Figs. 1 and 2.

When it is desired to make up an index, the sheets or cards, which in the drawings are indicated at g , are made out by a clerk and mounted in the holders. When a number of the holders have been thus equipped, they may be arranged in alphabetical or chronological or any desired order in a frame or unit, with the lowermost holder seated within the pocket formed of the base support or of an adjustable support as the case may be, and each succeeding higher holder seated in the socket or keeper of the next lower holder. In mounting them in the frame or unit in this manner, the holders may be nested so as to install a number of them at a time, or they may be independently mounted in the frame or unit.

When making up the index, whether the holders be handled singly or in groups, one end thereof is inserted under the overhung flange b' and the other end dropped within the oppositely disposed, parallel, vertically extending flange c , the holders when in this position being merely allowed to drop to place. When once in place, the nested holders will be held by the pocket of the support and by the inter-locking of the holders in such a way as to avoid the lifting of the end of any holder or holders adjacent the open flange c from the seat therefor upon the frame until such holder has been raised so as to clear the next lower holder.

Any desired number of holders may be used in a frame, within the capacity of the frame, and the holders may be removed and inserted singly or in groups as required, and the space normally occupied thereby filled by allowing the upper holders of a group to drop downwardly from their former position, or another holder may be substituted for the one removed.

To remove a single holder from a group, the holder immediately above the one to be

70

removed is raised by hand, the flange *g* being used to insure a firm grip upon this holder, raising all of the holders above that to be removed. When all these holders have been raised in this manner, the holder to be removed is also raised, the end of the holder next the flange *c* being raised from its seat and above the flange *c* and the holder moved laterally to carry its other end clear of the flange *b'*, thus permitting the holder to be removed from the frame.

If it is desired to remove two or more holders at a time, the operation is the same, excepting that all of the holders to be removed are simultaneously raised from the next lower holder not to be removed, and then moved to clear the flange *c* and the overhung flange *b'* in the manner above referred to.

20 By the construction herein described, the index rack may be quickly made up or changed, and the alphabetical or chronological order may be preserved without handling more than two of the holders for insertion or removal of an index sheet or card, the handling of one of these holders resulting in the simultaneous movement of all of the holders thereabove in one group.

The holders are preferably made each 30 from a single metallic blank to insure economy of production as well as lightness in the weight of the holders. The holders being uniform in size and seating each positively against the bottom of the socket or 35 keeper of the holder below it, the height of a column of holders standing in the frame will be very exactly proportionate to the number of holders in the column. The number of holders in the frame may thus be 40 readily determined by simply measuring the height of the column. When a plurality of our holders are mounted in a frame, the index portion thereof only is exposed, the greater portion of the holders overlapping 45 one another in a manner to permit a large number of such to be used in a single frame.

The use of a plurality of units or frames is merely for the purpose of permitting the expansion of an index system as required.

50 It is not our intention to limit the invention to the precise details of construction shown in the accompanying drawings, it being apparent that such may be varied without departing from the spirit and scope 55 of the invention as defined in the claims.

What is claimed is:

1. An index or information rack embodying therein a frame, a plurality of independently removable holders mounted in the 60 frame in successively abutting positions, means for retaining the holders normally in position in the frame comprising means carried by the frame for locking one of said 65 holders in position and interlocking means carried by the holders, and means carried by

each holder whereby an index sheet or card may be detachably mounted therein.

2. An index or information rack embodying therein a frame, a plurality of independently removable holders slidably mounted in the frame and resting normally in successively abutting positions, means for retaining the holders normally in position in the frame comprising means carried by the frame for locking one of said holders in 70 position and interlocking means carried by the holders, and means carried by each holder whereby an index sheet or card may be detachably mounted therein.

3. An index or information rack embodying therein a frame having parallel side flanges at least one of which has an inwardly extending overhang, a plurality of independently removable holders slidably mounted in the frame between said flanges and extending beneath said overhang and resting normally in successively abutting positions, means for retaining the holders normally in position in the frame comprising means carried by the frame for locking one of said holders in position and interlocking means carried by the holders, and means carried by each holder whereby an index sheet or card may be detachably mounted therein.

4. An index or information rack embodying therein a frame having side flanges one of which has an inwardly extending overhang and the other of which has no such overhang, a plurality of independently removable holders slidably mounted in the frame between said flanges and extending beneath said overhang and resting normally in successively abutting positions, means for retaining the holders normally in position in the frame comprising means carried by the frame for locking one of said holders in position and interlocking means carried by the holders, and means carried by each holder whereby an index sheet or card may be detachably mounted therein.

5. An index or information rack embodying therein a frame, side flanges thereon, at least one of which has an inwardly projecting overhang, a plurality of independently removable holders adapted to be seated and slide between said flanges and extend beneath said overhang, and interlocking means adapted to be rendered operative or inoperative by the sliding movement of said 115 holders, carried by said frame and said holders, whereby all holders in a frame are normally held therein.

6. An index or information rack embodying therein a frame, a plurality of independently removable holders nested in said frame and overlapped with a portion thereof exposed, index sheets or cards removably mounted on said holders, and signal sheets or cards separate from said index sheets or

- cards and distinctive therefrom removably mounted on one or more of said holders in front of said index sheet or card with a portion thereof exposed.
5. 7. An index or information rack embodying therein a frame, a plurality of independently removable holders mounted thereon, a socket or keeper on each said holder adapted to receive and support an adjoining holder, means carried by said frame whereby one of said holders is normally held therein, and means carried by each said holder whereby an index sheet or card may be detachably mounted thereon.
10. 8. An index or information rack embodying therein a frame having a base, a pocket carried thereby, a plurality of independently removable holders slidably mounted in said frame, the lowermost of which is adapted to be seated in said pocket and held in said frame thereby, a socket or keeper on each said holder adapted to receive and support an adjoining holder, and means carried by each said holder whereby an index sheet or card may be detachably mounted thereon.
15. 9. An index or information rack embodying therein a frame, and means for holding a series of index sheets or cards flatwise in said frame and overlapping to a predetermined extent, said means including a series of independently removable card holders each provided with interlocking and position determining means for co-acting with the next adjacent holder.
20. 10. An index or information rack embodying therein a frame having parallel side flanges at least one of which has an inwardly extending overhang, and means for holding a series of the index sheets or cards flatwise in said frame and overlapping to a predetermined extent, said means including a series of independently removable card holders each provided with interlocking and position determining means for co-acting with the next adjacent holder and being formed to be slidably seated on the frame between said side flanges and to extend beneath said overhang.
25. 11. An index or information rack embodying therein a frame having parallel side flanges one of which has an inwardly extending overhang and the other of which has no such overhang, and means for holding a series of index sheets or cards flatwise in said frame and overlapping to a predetermined extent, said means including a series of independently removable card holders each provided with interlocking and position determining means for co-acting with the next adjacent holder, said holders being formed to seat on said frame between said side flanges and to extend beneath said overhang, and the frame being provided
- with means for holding the first holder of the series in position in the frame.
12. An index or information rack embodying therein a frame, and means for holding a series of index sheets or cards flatwise in said frame and overlapping to a predetermined extent, said means comprising a series of independently removable card holders mounted to slide in the frame, each provided with interlocking and position determining means for co-acting with the next adjacent holder and each having a lower upwardly extending supporting and retaining flange adapted to hold an index sheet or card in position in the holder and an upper forwardly extending flange whereby the holder may be raised to permit the placing or removal of an adjacent holder or holders.
13. An index or information rack embodying therein a frame having a base, a pocket carried thereby, a plurality of independently removable holders slidably mounted in said frame, the lowermost of which is adapted to be seated in said pocket and held in said frame thereby, a socket or keeper on each said holder adapted to receive and retain an adjoining holder, a support adjustable in said frame and carrying a pocket adapted to receive and retain one of said holders, whereby the holders in a frame may be divided into independently operative groups, means whereby said adjustable support may be adjusted on said frame longitudinally thereof, and means carried by each said holder whereby an index sheet or card may be detachably mounted therein.
14. An index or information rack embodying therein a frame having parallel side flanges, and means for holding a series of index sheets or cards in said frame and overlapping to a predetermined extent, said means including a series of independently removable card holders each provided with interlocking and position determining means for co-acting with the next adjacent holder and being formed to be slidably seated on the frame between said side flanges, and the frame being provided with means for holding the lowermost holder in position in the frame and with an adjustable holder support for receiving and retaining one of the holders in position, said support being adjustable longitudinally of the frame whereby the holders in the frame may be divided into independently operative groups.
15. A card or sheet holder formed of a plate having means for holding a sheet or card positioned against the front face thereof, and a socket or keeper extending from the rear face thereof to receive an edge of a similar holder placed in position adjoining said holder.
16. A card or sheet holder having a sheet

supporting and retaining flange extending upward from the bottom thereof, and a socket or keeper extending outward and upward from its rear side to receive the bottom edge of a similar holder placed in position adjoining and above said holder, said socket or keeper being sufficiently above the bottom edge of the holder to permit the bottom of the holder to enter the socket or keeper of a similar holder placed in position adjoining and below said holder.

17. A card or sheet holder having a sheet supporting and retaining flange extending upward from the bottom thereof, a socket or keeper extending outward and upward from its rear side to receive the bottom edge of a similar holder placed in position adjoining and above said holder, said socket or keeper being sufficiently above the bottom edge of the holder to permit the bottom of the holder to enter the socket or keeper of a similar holder placed in position adjoining and below said holder, and said holder hav-

ing a forwardly extending card or sheet positioning flange at its upper edge whereby the holder may be lifted when nested with other similar holders.

18. The combination with a sheet or card holder formed to nest with a plurality of similar holders in relative position to leave a portion of a sheet or card removably mounted thereon exposed, of a sheet or card, and a signal sheet or card removably mounted on the holder in front of the first said sheet or card and formed to cover a portion only of the exposed part of the first said sheet or card.

In testimony whereof we have hereunto set our hands in the presence of two subscribing witnesses.
